UNITED STATES PATENT OFFICE.

HAROLD T. WARD, OF EAST ORANGE, NEW JERSEY, ASSIGNOR TO OTIS COMPANY, INC.,
OF WARE, MASSACHUSETTS, A CORPORATION OF MASSACHUSETTS.

DESIGN FOR A TEXTILE FABRIC.

Application filed October 2, 1926. Serial No. 19,233. Term of patent 3½ years.

To all whom it may concern:

Be it known that I, HAROLD T. WARD, a citizen of the United States, residing in East Orange, in the county of Essex, State of New Jersey, have invented a new, original, and ornamental Design for a Textile Fabric, of which the following is a specification, reference being had to the accompanying drawing, forming part thereof.

The figure is a plan view of a textile fabric showing my new design.

I claim:

The ornamental design for a textile fabric substantially as shown.

HAROLD T. WARD.
